UNITED STATES PATENT OFFICE.

MORTON E. PUGH, OF CHICAGO, ILLINOIS.

SKIMMER-SCOOP EXCAVATING MACHINE.

Application filed February 10, 1923. Serial No. 618,238.

To all whom it may concern:

Be it known that I, MORTON E. PUGH, a citizen of the United States, residing at Chicago, in the county of Cook and State of Illinois, have invented certain new and useful Improvements in Skimmer-Scoop Excavating Machines, of which the following is a specification.

The invention relates to skimmer-scoop excavators, in which the bucket or scoop travels along the boom which is raised and lowered during the operation of the machine, to cause the scoop to be filled and dumped.

The invention has among its various objects the provision of a means for actuating the scoop along the boom and the provision of a means for permitting the scoop to be dumped and automatically righted during its travel or descent along the boom prior to the lowering of the boom.

It is a further object of the invention to provide a carriage for the scoop, the scoop being pivotally connected to the carriage at one side and above the center of gravity of the scoop.

It is a further object of the invention to provide an improved locking means for the door or closure of the scoop.

In addition to the above, it is a further object to provide a means whereby the latch or holding means for the door of the scoop may be operated to open the closure or close it from either the platform to which the boom is secured, or from any other convenient position of the operator.

The invention will be explained in conjunction with the accompanying drawings, in which various arrangements of which the invention is susceptible are illustrated, it being obvious that changes and modifications may be resorted to without departing from the spirit of the appended claims forming a part hereof.

In the drawings,—

Fig. 1 is a side elevation of a skimmer-scoop excavator showing the boom in its raised and lowered positions with the scoop in a dumping and operating position; this structure being provided with a means for automatically causing the dumping and righting of the scoop.

Fig. 2 is an elevation similar to that illustrated in Fig. 1, showing a modified arrangement of the scoop, the righting device being eliminated.

Fig. 3 is a fragmentary view of a portion of the construction shown in Fig. 2, showing the scoop in a dumping position.

Figs. 4 and 5 are respectively end and side elevations of the mechanism employed for righting the scoop.

Fig. 6 is a plan view of the scoop shown in Figs. 1 and 2.

Fig. 7 is an end view of the scoop shown in Fig. 6.

Fig. 8 is a side elevation of the scoop.

Fig. 9 is an end elevation of the forward end of the scoop.

Figs. 10 and 11 are respectively end and side elevations of the scoop carriage.

Figs. 12 and 13 are views similar to Figs. 4 and 5 of the righting mechanism.

Figs. 14 and 15 are respectively edge and side views of a lever employed in the scoop structure, and

Figs. 16 and 17 are respectively end and plan views of a brake and drum mechanism employed in the structure.

Referring particularly to Fig. 1, a platform 10 is employed upon which the motor 11 and other driving elements are mounted, the platform being supported by the truck 12 which may be of any suitable or desired structure. A boom 13 is pivotally connected to the platform 10 at 14.

This boom is formed of a pair of channel beams 15 and 16 braced so as to provide the required strength, the braces including the frame work 17. The channel beams 15 and 16 are arranged so that the channel portions face outwardly to provide a track for the pairs of rollers 18 and 19, to which the scoop carriage generally designated 20 is secured. The scoop 21 is pivotally connected at 22 between the side frames 23 and 24 of the carriage. The pivotal connection 22 is arranged so that it will be positioned at one side and above the center of gravity of the scoop, which will insure the discharge of the scoop when released to permit of this and to assist in righting the scoop. The frame work 17 which is part of the boom 13 is provided with a sheave 25 over which a cable 26 rides. One end of this cable 26 is connected at 27 to some suitable portion of the boom and is extended over a sheave 28 and around the sheave 25 to another sheave 29, and then leads to one side of a tandem drum generally designated 30, the latter of which is of the usual construction, forms no part of my invention, and will

105
110

therefore not be described in detail, it being obvious that when the tandem drum 30 is rotated, it will either cause the boom 13 to be raised or lowered.

5 The boom 13 is further provided with a sheave 31 which is arranged adjacent the outermost end of said boom, and is provided to co-operate with a cable 32 which has one end, such as 33 thereof, secured to a suitable portion of the scoop carriage. The cable extends from its point of attachment 33 over the sheave 31 under the sheave 34 and has its opposite end secured to another portion of the tandem drum generally designated 10 30. Each drum of the tandem is independently operable of the other, as is customary in devices of this character, so that the scoop may be caused to travel towards the outermost end of the boom, and said boom raised 15 and lowered independently of the movement of the scoop.

As before stated, the scoop is provided with an automatically operated righting device, which is operable to permit the scoop 25 to assume a dumping position after the boom has been raised. This means includes the structure illustrated in Figs. 4, 5, 12 and 13, and includes the cables 35 and 36, which are respectively secured to the boom 13 at 30 37 and 38, the opposite ends of these cables being wound in opposite directions around a drum 39 with sufficient wrappings to permit the scoop to travel from one end of the boom to the other. The drum is provided 35 with a pinion 40, which meshes with a gear 41 which as clearly indicated in Fig. 4, is of a relatively larger dimension than the pinion. The gear 41 has a drum 42 arranged upon its shaft, around which are 40 wound the chains or cables 43, it being understood that one end of each of these chains is secured to the drum 42 and has its opposite end connected as shown at 44^b to the uppermost portion of the scoop.

45 This righting device is constructed so that when the scoop descends along the boom, which at this time is in a raised position, the scoop will be automatically caused to assume a position in which it is substantially parallel to the boom. It is manifest that as the scoop is drawn towards the outermost end of the boom through the medium of the cable 32, the cable 36 will cause the rotation of the drum 39 in one direction or in a 50 counter-clock-wise direction as viewed from Fig. 4. This motion will be transmitted to the gear 41 through the medium of the pinion 40 to the gear 41 and the drum 42, which will cause the chains 43 to be wound upon 55 said drum 42, causing the scoop to assume a position substantially parallel to the boom, or, in other words, in a skimming or scoop- 60 ing position.

65 The righting device illustrated in Figs. 4, 5, 12 and 13, is mounted upon a shelf or

platform 44 which extends between the sides 23 and 24 of the scoop carriage 20. This carriage is further provided with the abutments 45 against which the scoop 21 may 70 abut to limit its movement in one direction and to hold the scoop in its proper position during the scooping or excavating operation.

The mouth of the scoop 21 is provided with a mouthpiece 46, which extends from 75 the sides across the bottom of the scoop. The opposite end of the scoop is provided with a closure 47 which is hinged to the shaft 48 through the medium of hinged elements 49, the shaft 48 being secured to the top of the 80 scoop through the medium of the brackets 50. A lever 51 is pivotally secured to the shaft 48 so that it may move with respect thereto. This lever is provided with an arm 52 and another arm 53. One strand of a 85 cable 54 is attached through the medium of a suitable clevis to the arm 52 of the lever 51. The opposite end such as 53, of this lever, rests against the closure 47 of the scoop. This closure 47 is provided with a 90 bolt or latch 55 which is secured to the closure through the medium of the clips 56. This bolt 55 has another strand such as 57 of the cable 54, secured to it, the strand being provided to cause the release of the 95 latch and the opening of the closure upon the operation of the latch. The bolt 55 co- 100 operates with a latch element 58, which is secured to same stationary portion of the scoop. The cable 54 extends around a drum 59 which also has one end of a cable 60 wrapped around it, from which it extends over a movable sheave 61, it being extended downwardly towards the platform and connected at 62 to said platform. The sheave 105 61 is held by means of the cable 63 and the sheaves 64 and 65 towards the uppermost portion of the frame work mounted on the platform 10, it being of course understood that one end of the cable 63 is secured to 110 the sheave 61 and has its opposite end provided with a weight 66. This arrangement will permit the sheave 61 to travel between the sheave 64 and the floor of the platform 10, and thus cause the weight 66 to be raised 115 and lowered. The purpose and object of this structure will presently be apparent. The cable drum 59 is provided with a friction drum 67, with which the brake-band 68 co-operates, the latter of which is connected to the foot lever 69 having the releasable holding dog 70 secured thereto which co-operates with the pin 71 to hold the lever in its lowermost or braking position.

120 A short cable 72, one end of which is connected to the lever 69 and has its opposite end secured to the portion 73 of the drum 59 is provided to rotate the drum 59 and cause the release of the bolt 55 of the latch carried 125 130

by the scoop, and may also be operated to right the scoop after it has assumed a dumping position.

The structure just above described is further employed to control the movement of the scoop relatively to the boom and thereby prevent its assuming a dumping position until permitted to do so by the operator. From the foregoing description it is evident that as the scoop travels towards the outermost end of the boom, it will gradually assume a dumping position or the position shown in full lines in Fig. 1. During this travel, the line 54 will be held more or less taut, which will control the movement of the scoop to a dumping position. Upon the release of the rope 54, the scoop will assume the position illustrated in full lines in Fig. 1, and when a pulling strain is exerted upon this cable 54, the bolt 55 of the latch will, through the medium of the strand 57, be actuated to cause the release of the latch, which will permit the closure 47 to open and discharge the contents of the scoop. When the parts of the scoop have assumed this last named relation, the rope 54 may again be pulled upon to actuate the lever 51, which will cause the door to be slammed against the scoop to jar loose any material from the interior of the scoop which may tend to adhere thereto. It is manifest that as the scoop travels downwardly or descends the boom 13, the righting mechanism illustrated in Figs. 4 and 5 will cause it to assume a substantially parallel relation with respect to the boom. When the scoop assumes this substantially parallel relation relatively to the boom, the closure 47 is caused to automatically assume a closed position. The subsequent lowering of the boom causes the scoop to be positioned so that when it is drawn towards the outermost end of the boom by means of the cable 32, it will engage the surface to be excavated and scoop the material therefrom, after which a repetition of the previously described operation will cause an actuation of the mechanism in a manner similar to that referred to.

It will be noted that the closure such as 47 will automatically assume a closed position when the scoop is moved to assume a position substantially parallel with the boom, this being due to the construction of the scoop and the position of the pivot or shaft 48 of the door or closure, it being apparent by reference to Fig. 8, that the rear ends of the side walls of the scoop are arranged at an angle to the top and bottom walls of the scoop.

In the modified arrangement illustrated in Figs. 2 and 3, the automatic righting device such as illustrated in Figs. 4 and 5 is dispensed with. The scoop and carriage is moved towards the outermost end of the boom 13^a by means of the cable 32^a in a

manner similar to that described in connection with the structure shown in Fig. 1. It will also be noted that the pivot of the scoop 21^a is arranged at one side and above the center of gravity of the scoop, so that it may be readily dumped and moved from its dumped position to a position in which it is again substantially parallel with the boom, by means of the cable 54^a. The cable 32^a has one end secured as at 33^a to the carriage of the scoop and travels over a sheave 31^a and under a sheave 34^a, the opposite end of the cable being connected to one of the tandem drums 30^a mounted on the platform of the machine. As the scoop and carriage are moved outwardly upon the boom by means of the cable 32^a, the rope 54^a is held more or less taut by the drum 59, and the brake mechanism 68^a, the latter of which may be of any ordinary or usual structure, whereby the drum 59^a may be releasably held against movement.

During the travel of the scoop towards the outermost end of the boom, the cable 54^a is held taut and fed off from the drum 59^a so that the scoop will be held against assuming a dumping position until the brake mechanism is released to permit it to discharge the material contained in the scoop. The cable 54^a is connected to a lever 51^a which is similar in structure and function to the lever 51 shown and described in connection with the structure of the scoop illustrated in Figs. 1, 6, 7 and 8. The closure 47^a of the scoop is provided with a bolt 55^a which is connected to the cable 54 through the chain strand 57^a which will cause a pull to be exerted upon the bolt when the scoop assumes a dumping position so as to release the closure for the scoop. This arrangement also permits the closure to be slammed against the end of the scoop to jar loose any material which may tend to adhere to the interior thereof.

A brake mechanism which co-operates with the drum 59^a illustrated in Fig. 2, includes the foot lever 68^a which is secured to the shaft 90^a and has a lever 89^a extending therefrom. This lever 89^a is connected at 88^a thru the medium of a link 91^a to one end of a lever which is pivoted at 87^a. The opposite end of the lever has one end of a brake band 85^a secured to it as designated at 86^a. The opposite end of the brake band is secured to some stationary portion of the structure and it is manifest that as pressure is applied to or released from the lever 68^a the brake band 85^a will be caused to co-operate and release the brake drum 59^a and provides an arrangement for controlling the rope or cable 54^a and will thus hold the scoop against assuming a dumping position and is operable to release the closure and permit it to be slammed against the end of the scoop to jar any material which may

adhere to the interior of the scoop therefrom.

From the foregoing description, and particularly that relating to the structure illustrated in Fig. 1, it will be evident that a means is provided whereby the scoop is automatically righted from a dumping position to a digging position, as it descends the boom, in which position it will be retained during the digging operation, and released to permit it to dump the contents of the scoop when it reaches the desired position relative to the outermost end of the boom.

It is also manifest that the pivotal connection between the carriage and the scoop is arranged at one side and above the center of gravity of the scoop, which will insure its dumping and also assist in more readily righting the scoop after it has performed the dumping operation.

It is further manifest that the cable or pull line 54 or 54^a in the structure illustrated in Figs. 2 and 3 performs the function of righting the scoop, unlatching the lock and the closing of the door.

It is further apparent that another object and advantage attained by the invention, is the provision of a scoop operating mechanism adapted for and operable on the different types of excavating machines, such as are in use at the present day, to the end that such mechanism can be operated on all such machines without any alteration in the machine whatever. It is a well known fact that about half of the excavating machines in present use are provided with two power driven drums only, and about the other half of the excavating machines in use at the present time are provided with three power driven drums.

In the case of the machines which have only two power driven drums it is manifest that an auxiliary righting device must be provided for righting, dumping, and adjusting the scoop. However, if the machine is of the three power driven drum type, including brakes, as shown in Fig. 2, the above mentioned auxiliary righting device is dispensed with.

Having thus fully described my invention, what I claim as new and desire to secure by Letters Patent is:

1. In a machine of the character described having a boom, a scoop, operable along said boom, means for dumping the scoop, and means for automatically righting said scoop from its dumping position as it travels along said boom.

2. In a machine of the character described having a boom, a scoop operable along said boom, means for dumping the scoop, and means for automatically righting said scoop from its dumping position as it travels along said boom to a digging position.

3. In a machine of the character described

having a boom, a scoop operable along said boom, means for dumping the scoop, and means for automatically righting said scoop from its dumping position as it travels along said boom, said means being operable to permit said scoop to assume a dumping position.

4. In a machine of the character described having a boom, a carriage arranged for movement lengthwise of said boom, a scoop pivotally connected to said carriage, means permitting the scoop to be dumped and means for automatically righting said scoop from said dumping position, said means being mounted upon said carriage.

5. In a machine of the character described having a boom, a scoop operable along said boom, means for dumping the scoop and means for automatically righting said scoop from its dumping position as it travels along said boom, said means including a cable one end of which is secured adjacent an end of said boom.

6. In a machine of the character described having a boom, a scoop operable along said boom and means for automatically righting said scoop as it travels along said boom, said means including cables the ends of which are secured adjacent the opposite ends of said boom.

7. In a machine of the character described having a boom, a scoop operable along said boom, means for dumping the scoop and means for automatically righting said scoop as it travels along said boom, said means including a drum and a connection between said drum and the scoop.

8. In a machine of the character described having a boom, a scoop operable along said boom, means for dumping the scoop and means for automatically righting said scoop from its dumping position during its travel along said boom, said means including a rotatable element cooperatively connected to said scoop.

9. In a machine of the character described having a boom, a scoop operable along said boom, means for dumping the scoop and means for automatically righting said scoop from its dumping position during its travel along said boom, said means including a drum, a cable arranged to actuate said drum and a connection between said drum and said scoop.

10. In a machine of the character described having a boom, a scoop operable along said boom and means for automatically righting said scoop as it travels along said boom, said means including a drum, cables, the ends of which are secured to said boom, and are cooperatively connected to said drum, and a connection between said drum and said scoop.

11. In a machine of the character described having a boom, a scoop carried by

said boom and being operable along said boom, said scoop having a closure, a latch for the closure, a pull line connected to said closure, said pull line being operable to assist in righting said scoop, operate the latch, to release said closure, and to close said closure.

12. In a machine of the character described having a boom, a scoop operable along said boom and means for automatically righting said scoop as it travels along said boom, said means including a drum, cables the ends of which are secured to said boom and are cooperatively connected to said drum, a rotatable member operable upon the actuation of said drum, and a flexible element connected to said last mentioned rotatable member and said scoop.

13. In a machine of the character described having a boom, a scoop operable along said boom, and means for automatically righting said scoop as it travels along said boom, said means being operable to permit said scoop to assume a dumping position, including a drum, cables the ends of which are secured to said boom and are cooperatively connected to said drum, a rotatable member operable upon the actuation of said drum, and a flexible element connected to said last mentioned rotatable member and said scoop.

14. In a machine of the character described having a boom, a scoop operable

along said boom, means for dumping the scoop and means for righting said scoop and pulling it back into digging position, said means including a power driven drum operable along the boom with the scoop and a flexible connection between said drum and said scoop.

15. In a machine of the character described having a boom, a scoop, the scoop being operable with said boom, means for tensioning the outward travel of said scoop and preventing premature discharge of its contents, said means including a holding brake mechanism cooperating with a drum, and flexible connections between said drum, and said scoop, said connections being controlled by said brake mechanism.

16. In a scoop operating mechanism of the character described having a movable boom, a scoop operable along side of said boom, a closure for said scoop, means for unlatching the closure of said scoop said means being provided on said closure and permitting it to swing to vertical position for discharge of its contents, said means including a brake, a drum, and a flexible connection having three ends, one end attached to said drum, one end connected to the unlatching device located on the closure, the third end being connected to a pulling and closing member located on the upper rear end of said scoop.

MORTON E. PUGH.
